CRUSHER

Jens C. Holm, Front Royal, Va., assignor to Bath Iron Works Corporation, Bath, Maine, a corporation of Maine
Original application Oct. 31, 1955, Ser. No. 543,922, now Patent No. 2,873,920, dated Feb. 17, 1959. Divided and this application Dec. 11, 1958, Ser. No. 779,665
4 Claims. (Cl. 241—84)

This invention relates to a rotary type crusher for reducing frangible material.

This is a division of my co-pending application Serial No. 543,922, filed on October 31, 1955, and entitled "Crusher," now issued as Patent No. 2,873,920 on February 17, 1959.

An object of this invention is the reduction of frangible material and the recirculation of the material requiring further reduction.

Another object of the invention is to repeatedly subject the frangible material to the impact action of hammers rotating at a high speed until the material is reduced to a given size.

Another object of the invention is to provide a crushing machine which discharges the reduced material of proper size and recirculates the oversized material into the path of the high speed hammers.

A further object of the invention is to provide a crusher for reducing wet material.

A still further object of the invention is to provide a crushing machine for reducing frangible materials to fine particles and removing the particles by an air stream.

Other and further objects will be apparent from the following description taken in connection with the drawings in which:

FIG. 1 is a longitudinal sectional view of the crusher for producing fine particles;

FIG. 2 is a cross sectional view of the crusher;

FIG. 3 is a sectional view taken along lines 3—3 of FIG. 1;

FIG. 4 is a fragmentary sectional view of another embodiment of the rotor;

FIG. 5 illustrates a portion of another embodiment of breaker bars comprising a double row of the breaker bars;

FIG. 6 illustrates another embodiment of the breaker bars with rectangular shape; and

FIG. 7 illustrates another embodiment of the breaker bars with an elliptical shape.

The crusher comprises a rotor 10 having a set of hammers 11 for hitting frangible material with impact blows, sending it against the rotating breaker means or bars 12 encircling the rotor 10. A solid plate 77 exteriorly encircles the breaker means and rotates therewith to retain the frangible material within the breaker in cooperation with radially extending walls. The material is introduced into the crusher through an opening 14 between the breaker means 12 and the rotor 10 and is discharged as finely comminuted material through the discharge passage 79 in the tubular trunnion 76 supporting and rotating the breaker bars about the rotor.

The rotor 10 is supported on the end of the shaft 34 which is coupled to and driven by a prime mover such as an electric motor 16. The rotating hammers 11, subscribing a hammercircle having a diameter A (FIG. 2), have surfaces substantially radial to the shaft 34 and extending longitudinally to the axis for hitting material dropped in the crusher. The hammers are of the replaceable type and are secured in fixed position. As shown in FIG. 2, the hammers are adapted to rotate in one direction. Hammers may be provided striking surfaces on both sides so that the direction of rotation of the rotor may be reversed.

2

This is illustrated in the embodiment shown in FIG. 4 in which the hammers 11 have faces 11a, 11b on opposite sides and are pivotally mounted on the rotor.

The breaker means or bars 12 are spaced a distance B from the hammercircle, FIG. 2, and extend longitudinally to the hammers 11 to form breaker surfaces facing the hammers to receive the projected material. The bars 12 are uniformly spaced to provide spaces 17 having a width E for passing material therethrough.

10 The breaker bars 12 are equally spaced from the rotor 10. The breaker bars 12 are rigidly secured to a supporting means comprising a flat, circular mounting plate 18 welded or otherwise fastened to the end of the trunnion 76 and having radially extending support beams 19 stiffening the plate 18 and rigidly securing the plate 18 to the trunnion 76. The breaker bars 12 are preferably cylindrical in shape with a longitudinal bore 20 extending therethrough. Each of the bars is secured to the mounting plate 18 by means of a long bolt or threaded shaft 12a extending through an opening in the plate 18 and the bore 20 of the respective bar and threading into the rim 21 positioned at the other end of the bar 12. Supports 21a are peripherally arranged securing the rim 21 to the plate 18 along the outer edge. The rim is thus securely held 25 to the plate 18 by the bolts 12a, supports 21a and plate 77. The rim has an inner circular edge 22 forming a circular opening with the circular lining on the rotor 10. The bars have a diameter D and the holes or openings 23 are spaced so that the surfaces of the bars are spaced the distance E 30 through which material may readily pass to the chamber 13 and back into the crushing chamber or zone.

The trunnion 76 is tubular in shape and has an inner cylindrical wall 80 forming the discharge passage 79 and has an outer surface 81 forming a journal fitting in the bearing 82. A helical conveyer 86 is mounted on the wall 80 and rotates, as indicated by arrow A, to return oversized material entering the passage 79 to the comminuting zone. Recessed in the passage 79 from the discharge opening 75 is an impact plate 83 supported by spaced struts 84 to provide openings 85 through which the pulverized material passes. Oversized material projected into the passage 79 hits the impact plate and drops onto the surface 80 to be returned by the conveyer 86. The outer end of the trunnion 76 is coupled to a conduit 87 by means 45 of the flanges 88 and 89 and bolts 90. The conduit 87 is connected to the suction means (not shown).

The bars 12 instead of being cylindrical may be shaped to have a flat comminuting surface as illustrated in FIG. 6 by bars 98 facing the hitting surface of the hammers 11 on 50 the surfaces or may have a convex elliptical surface 100 facing the hammers 11, FIG. 7.

The plate 77 is secured to the outer edge of the supporting plate 18 and flange 21. The reduced material passes through the space between the bars and drops into 55 the chamber 13. The material passing between the breaker bars collects on the curved plate 77 and is carried up to the top of the breaker by a grated scoop 26 positioned between a breaker bar and the plate 77 and dropped into the path of the rotor hammers for further fragmentation. The scoop is formed by a row of spaced bars 26a extending between one of the breaker bars and the plate 77. The bars 26a are rigidly secured to the bars 12. The scoop bars are set at an angle to a radial line so that material is picked up and passed through the 60 breaker bars and carried upwardly above the rotor 10. The angle of the scoop to a radial line is such as to carry the material over the rotor before it is passed from chamber 13 between the bars into the crushing zone. A single scoop is shown but a plurality of scoops may be provided 65 to produce a substantially even flow of material from the chamber.

The breaker means 12, the plate 77 and the trunnion 76

are rotatably mounted in the bearing 82 which is axially aligned with the shaft 34. The casing 27 has sides 35, 36 extending between the end walls 37 and 38. The end walls are supported by pillars 39 and 40 which are securely embedded in a concrete base 41. A stationary curved wall 43 extends from end wall 37 to end wall 38 and underneath the rotating plate 77. The side walls 36 extend above the end walls 37 and 38 and have an upper semi-circular edge 42, 43. The top of the casing has covers 44, 45 pivotally mounted to the top edge of the end walls 37, 38 for opening the top of the casing to inspect the comminuting members and sealing the casing by resting on the edges 42, 43. The rectangular opening 14 is provided in the wall 36 to permit the passage of material from the feed chute 28 into the comminuting members in the casing 27. The opening 14 is positioned intermediately between the end walls 37, 38 and above the hammercircle subscribed by the rotating hammers 11 and the breaker bars 12. The wall 36 is provided with wear-resistant lining plates 46a, 46b, 46c, and 46d. All the plates together form a circle and fit in the opening 30 formed by the rim 21. A mechanical seal is mounted around rotor shaft 34. The upper plates 46c and 46d are formed to fit around the opening 14 in the wall 36 to pass the material into the crusher.

The shaft 34 and rotor 10 are supported by bearings 49 and 50 and are connected through coupling 51 to a motor 16. The rotor and bars are mounted on a frame 52 slideably mounted on a pair of fixed runners 53 secured to the base 41. Thus, the rotor 10 and the resistant plate 47 may be conveniently withdrawn from the crusher for inspection and replacement of worn hammers or parts. The frame 52 is located in position on the stationary runners 53 by bolts 54 fitting through bosses 55 and nut 56 on the frame and runners, respectively.

The trunnion 76 has flanges 57, 58 between which the bearing 82 is positioned. The bearing 82 supports the trunnion 76 in axial alignment with the rotor shaft 34, and the flanges 57, 58 restrict the axial movement of the trunnion 76 to a minimum. The bearing 82 has flanges 60 and 61 engaging the flanges 57, 58 on the trunnion 76. The trunnion 76 is turned by means of a gear 92 and a worm 91. The gear 92 is bolted to the flange 64 which is rigidly secured to the trunnion 76. The worm 91 is driven by an electric motor or other suitable power source (not shown) by means of shaft 93. The bearing 82 and gear 92 and worm 91 are sealed in the casing 94. An oil seal 95 is provided on the trunnion 76 in the casing wall 35 to exclude dust and other abrasive material from entering the chamber. The bearing 82 is mounted on the base 71 which is in turn supported by the base 41. Thus, the trunnion 76 and shaft 34 are held from axial movement and in axial alignment during operation. The breaker means 12 is rotated slowly by means of the gear 92 and worm 91. The rotor 10 is turned at a high rate of speed SH.

The rotor may have pivoted hammers as shown in FIG. 4 and the fixed hammers may have striking surfaces 11a, 11b back to back so that the rotor may be reversed in direction. The breaker bars 12 and the rotor 10 are preferably driven in the same direction with the rotor 10 turning at a high speed. The breaker bars 12 are rotated at a substantially slower speed SL to carry the oversize material to the top of the crushing zone. The rotor 10 and the breaker bars 12 may be rotated in the same direction SHR or in opposite directions. It is preferable to reverse the relation of the direction of rotation by reversing the direction of rotation of the rotor 10 so that it will not be necessary to change the angle of the scoop 26.

The breaker bars 12 have been described and illustrated as having circular breaker surfaces. The bars 98 may be rectangular in shape with flat striking surfaces, FIG. 6.

The bars may be elliptical in shape as illustrated by bars 100 in FIG. 7 to form convex elliptical breaker surfaces facing the rotor 10. Also instead of a single row of breaker bars, a double row of breaker bars 96 and 99, FIG. 5, may be provided with the spaces between the bars being of a sufficient width to pass material having a size of the entering material. The bars 96 and 99 may be arranged in separate inner and outer concentric rows. The material may be picked up by the scoop or scoops 26 and dropped back through the spaces into the rotor. The material hit by the hammers passes between the bars of the first row and strikes the second row of bars.

The material that is initially hit by the hammers against the breaker means may, in the embodiment described and illustrated, either pass between the bars after reduction and be carried up to the top of the crusher from where it may be dropped into the rotor again or the oversize material, instead of passing through the bars, may collect in the bottom of the breaker means and be tumbled therein accumulating until there is a sufficient amount so that the hammers engage the material tumbling on top of this accumulated pile. The hammers will strike these top pieces to further reduce them. The breaker bars may carry some of the pieces between them over the top of the crushing zone and drop the pieces into the rotor.

This material tumbling in the bottom of the breaker means assists in keeping the breaker bars clean when wet sticky material is fed to the crusher. The continual rotation of the breaker bars and the rubbing of the bars by the accumulated material maintains the bars substantially free of foreign matter so that the impact surfaces remain hard.

The spacing E will depend upon the speed of rotation of the breaker means 12 and the speed of rotation of the hammers 11. The greater the speed, the wider the spacing E may be. The diameter of the rotor 10 and the distance B will depend upon the material to be crushed, the speed of rotation of the rotor 10, and the size of the entering material.

In FIG. 1 the solid plate 77 retains the material within the rotating members. The frangible material is introduced into the crusher and retained within the rotating members until reduced to fine particles that are removed from the crusher by a stream of air entering through the opening 14 and leaving the chamber through the passage formed by the tubular trunnion 76. The air is drawn out by suction means such as a fan (not shown), and the particle laden stream passes through a cyclone separator (not shown) to clear the air of the particles and collect them at the bottom of the separator.

Various modifications and changes may be made in the crusher without departing from the invention as set forth in the appended claims.

I claim:

1. A crusher for pulverizing frangible material to fine airborne particles comprising a rotor having hammers, breaker bars circumferentially arranged around said rotor and radially spaced from said hammers to receive said material by impact, a tubular trunnion having a longitudinal discharge passage therethrough axially aligned with said rotor, a mounting plate secured to said trunnion for supporting said breaker means, a curved plate circumferentially positioned and radially spaced outwardly from said breaker bars and enclosing said breaker bars in cooperation with said mounting plate, a flange extending radially inwardly from said curved plate on the opposite side of said breaker bars from said mounting plate and forming an opening with the lower portion above the rotor and feed means for passing frangible material through said opening into said crusher, above said rotor, means between said breaker means and said curved plate to return material through said bars reducing said mate-

rial to fine particles for withdrawal as a suspension through said trunnion.

2. A crusher as claimed in claim 1 wherein said breaker bars are cylindrical in shape.

3. A crusher as claimed in claim 1 wherein a feed opening for introducing material into said crusher is positioned at the side of said crusher and within the periphery of said breaker means.

4. A crusher as claimed in claim 1 wherein said breaker means comprises two concentric rows of cylindrical breaker bars with the bars of the outer row spaced outwardly from the space between two bars of the inner row and each outer bar spaced from said inner adjacent bars a distance for returning the oversize pieces into the path of the rotating hammers.
